UNITED STATES PATENT OFFICE.

ALBERT BALL AND GEORGE F. CASE, OF CLAREMONT, NEW HAMPSHIRE.

DEVICE FOR FEEDING DIAMOND AND OTHER ROTARY ROCK-DRILLS.

SPECIFICATION forming part of Letters Patent No. 247,872, dated October 4, 1881.

Application filed August 8, 1881. (No model.)

To all whom it may concern:

Be it known that we, ALBERT BALL and GEORGE F. CASE, both of Claremont, in the county of Sullivan and State of New Hampshire, have invented a new and Improved Device for Feeding Diamond or other Rotary Rock-Drills; and we do hereby declare that the following is a full and exact description of the same, reference being had to the accompanying drawing, and to the letters of reference marked thereon.

Our invention relates to an improvement in the method of feeding diamond or other rotary drills; and it consists, essentially and principally, in the use of a direct-acting single cylinder, in combination with a revolving feed-rod carrying the drill-rod arranged inside of such cylinder, and having secured to such feed-rod in the cylinder a piston, whereby the rods are moved forward or back when pressure is applied thereon; and it further consists in the combination of such parts with a reversing-valve arranged on the side of the cylinder, outlet and inlet governing valves, and conducting-pipes; and, further, in the method of feeding direct from a boiler to the cylinder; and, lastly, in the arrangement of mechanism with such parts for operating the drill, all as more fully hereinafter described.

In order that those skilled in the art may know how to make and use our invention, we will proceed to describe the same, reference being had to the accompanying drawing, which is a part longitudinal section, showing clearly our improvements therein.

Like letters denote corresponding parts in the drawing.

A represents the frame end, held by a clamp at *a* in the usual manner for this class of drills. Upon the projecting portion of this frame is bolted the cylinder *B*, provided at each end with a stuffing-box, *b*, constructed and arranged in the ordinary manner.

C is the revolving feed-rod, passing longitudinally through the cylinder and stuffing-boxes *b* at each end of the cylinder, and extending outwardly for some distance beyond each end. This revolving feed-rod carries the hollow drill-rod *D*, which is secured to it by the clutch *e* and its screw *c'*, near the lower end, which clutch also enables the drill-rod to

be lowered when a greater depth is required to be reached. This feed-rod *C* is revolved by a spline on the bevel-pinion *E*, which meshes with the bevel driving-gear *E'*. This rod is provided with a longitudinal slot, *d*, in which the spline of the pinion slides when the rod advances. The guide *e* serves to steady the lower end of the feed-rod, and also serves as a bearing for the bevel-pinion *E*.

In the cylinder, and to the feed-rod *C*, is secured a piston, *F*, with which rod it revolves. It is of the ordinary construction, and may be filled with suitable wood, hard rubber, celluloid, or other material that will not be affected by the liquid in the cylinder, nor itself wear the cylinder, nor be worn by it. This piston performs the operation of advancing and withdrawing the rods when pressure is exerted thereon.

On the side of the cylinder *B*, and cast with it, is a small cylinder, *B'*, in which operates a reversing-rod, *G*, provided at its upper and near its lower end with a valve, *f*. When this rod is raised, which is by means of the small lever *g* at its lower end, the valves *f* so operate as to permit the liquid to pass through an opening, *h*, (cut in the side of the cylinder near the upper end,) into the cylinder above the piston, thereby forcing the drill downward, the velocity of feed being governed by the amount of liquid allowed to flow out through the governing-valve *i* at the lower end of the cylinder *B'*.

By lowering the rod *G*, which is effected by the same means as raises it, the liquid passes through an opening, *h'*, (near the lower end of the cylinder, and which is similar to the opening *h* at the upper end,) into the cylinder below the piston, thereby forcing the drill up, the speed of which is governed by the valve *i* at the upper end of the cylinder *B'*.

We have shown in the drawing a simple method for supplying under pressure water or other liquid to the cylinder, which method enables the use of the same water repeatedly, as in many cases it may not be convenient to be had at all times, and it is therefore necessary to use the same water as often as possible.

k is an inlet-pipe connecting with the small cylinder *B'*, and through which the water or liquid under pressure is supplied to the cylin-

der B. This pressure may be obtained by pump H.

It will be seen that by this arrangement the same water is used repeatedly, as the supply to the pump is only as much as is permitted to flow out of the governing-valves i i' through the outlet-pipe k' to the tank or reservoir I. The pipes k k' can be made of flexible material, to allow the placing of the drill at various angles (when so desired) without interfering with the pump.

Although we have described this method of supplying water to the cylinder, we lay no special claim to it, for any convenient one may be used; but as part of our invention we do lay claim to the method of supplying pressure to the piston by making a direct connection from the water-leg of a steam-boiler to the cylinder, as shown in the drawing. J represents the boiler, and m m' m'' the valves by which the water is pumped into the boiler, and conducted therefrom, through the inlet-pipe k and valve m to the cylinder, in the manner before explained.

The pressure of the steam in the boiler is equal to the pressure of the water in the cylinder. If the cylinder be filled with water or other liquid, and pressure be applied to the upper end, the piston will travel only so fast as the water is permitted to escape from the lower end thereof. At the same time the piston and rod are free to revolve, thus permitting a progressive rotary motion to the feed and drill rods, without having any loose joints between the drill and feeding mechanism, the piston revolving against the pressure of water that forces it forward.

It will be evident, upon inspection, to those skilled in the art to which our invention pertains that its facilities for performing the work for which it is intended are the very best, from the fact that its component parts are very few and simply arranged, when compared with the many such complicated devices now in use; and in consequence of its parts being few it is necessarily cheap, simple, and very light in weight. It can bore a hole at various angles and of an unlimited depth, as the drill-rod, by means of the clutch and its screw, can be so adjusted to enable it to reach any depth desired.

Having thus described our invention, what

we claim, and desire to secure by Letters Patent, is—

1. In a rotary drill, the combination of the driving mechanism, rotary feed-rod, and piston, substantially as described, with a drill-rod passing longitudinally through the entire length of such feed-rod, and made adjustable thereto by means of a clutch and screw, substantially as described, and for the purpose set forth.

2. In a rotary drill, the combination, with a direct-acting cylinder, rotary feed and drill rods, and piston, arranged substantially as described, of openings made in the side of said cylinder, near its upper and lower ends, for the inlet and outlet of water in such cylinder, and a reversing-rod provided with an upper and lower valve to regulate the flow of water through such openings, substantially as described.

3. In a rotary drill, the combination, with a direct-acting cylinder, rotary feed and drill rods, piston, openings, and reversing-rod, arranged substantially as described, of outlet-governing valves, substantially as described, and for the purpose set forth and shown.

4. In a rotary drill, the combination of the cylinder B, openings h h' , reversing-rod G, governing-valves i i' , and pipes k k' , constructed and arranged substantially as described, with any suitable pressure-supply, for the purpose set forth.

5. In a rotary drill, the combination, substantially as described, of the cylinder B, piston F, rotary feed and drill rods C D, openings h h' , reversing-rod G, governing-valves i i' , pipes k k' , steam-boiler J, and valves m m' m'' .

6. In a rotary drill, substantially as described, the combination of the drill-rod D with the feed-rod C, and clutch e, with its screw, substantially as described, and for the purpose set forth.

This specification signed and witnessed this 16th day of May, 1881.

ALBERT BALL.
G. F. CASE.
